UNITED STATES PATENT OFFICE.

EDWARD P. HOWLAND, OF WORCESTER, MASSACHUSETTS.

IMPROVEMENT IN CAR-COUPINGS.

Specification forming part of Letters Patent No. 39,927, dated September 15, 1863.

To all whom it may concern:

Be it known that I, EDWARD P. HOWLAND, of Worcester, in the county of Worcester and State of Massachusetts, have invented a new and Improved Car-Coupling; and I do hereby declare that the following is a full, clear, and exact description of the same, reference being had to the accompanying drawings, making a part of this specification, in which—

Figure 1 is a longitudinal vertical section of my invention, taken in the line *x x*, Fig. 2; Fig. 2, a plan or top view of the same.

Similar letters of reference indicate corresponding parts in the two figures.

This invention relates to an improved car-coupling of that class which are commonly termed "self-coupling;" and it consists in the employment or use of a combined weight and pin, in combination with a sliding pin-support and two springs, all arranged in such a manner that the link is enabled to secure itself in the draw-head when forced therein and retained in a horizontal position when in one draw head only, and the link prevented from being bent in case of the adjoining draw-heads of two cars coming in contact.

To enable those skilled in the art to fully understand and construct my invention, I will proceed to describe it.

A represents the draw heads of two cars. These draw-heads may be of the usual or an approximate form. Each draw-head has a rectangular slide or bar, B, fitted vertically in it, and allowed to slide freely up and down, and to the upper surface of each draw-head a vertical plate, C, is attached, in which a slot, *a*, is made vertically, and through which pins or screws *b* pass into the upper parts of the bar B, said pins and screws serving as stops for the bars B. Each bar B is provided at its lower end with a projecting pin, *c*, which, when the bars B are fully down, fit in recesses *d* in the bottoms of the draw-heads, as shown in one of the draw-heads in Fig. 1. In each draw-head A there is a slide, D, to which a rod, E, is attached. These rods E extend within boxes F in the draw-heads, and the inner ends of said rods are fitted loosely in guides or bearings *e* in the boxes F. On each rod E there is fitted a spiral spring, G, the front ends of which bear against pins *f* in the rods E, and the back ends bear against the

guides or bearings *e*, as shown clearly in Fig. 1. In the back part of each box E there is fitted a rod, H. The front ends of these rods are fitted in the guides or bearings *e*, and their back ends are fitted in bearings *g* in the backs of the boxes F and draw-heads. On each rod H there is placed a spiral spring, I. The front ends of these springs bear against pins *h* in the rods H, and the back ends bear against the back parts of the boxes F. These springs I are considerably thicker, heavier, or stronger than the springs G, as shown clearly in Fig. 1. The boxes F completely inclose the springs, and effectually protect them from the weather. The boxes may be secured in the draw-heads by having their back ends filled in recesses *i* in the backs of the draw-heads and their front parts secured by screws *j*. When the bars B are raised, the springs G will keep the slides D forced outward underneath the bars B, so as to keep them in an elevated state, as shown in one of the draw-heads in Fig. 1. When the link J is shoved into one of the draw-heads, the slide D thereof is forced back, the spring G yielding, and the bar B falls upon the link, the pin passing through the link into the recess *d*. The rod E, in being thus forced back, just comes in contact with the end of the rod H, as shown in Fig. 1, but does not pass against it. The link J is held in a horizontal position by the bar B, and when the empty draw-head approaches the one containing the link, the other will be in line with the former, and the slide D of the empty draw-head will be forced back, the spring I of the draw-head containing the link on account of being stronger than the springs G, causing the latter behind the moving slide to yield, thereby allowing the bar B to drop and the pin *c* to pass through the link. The springs I, where the draw-heads are connected, admit of the slides D yielding under the irregular movement of the cars, and thereby prevent the link being bent, and said springs also prevent violent concussions, which would otherwise ensue in case of the draw-heads coming together.

I do not claim a drop-pin and a sliding support therefor, for that is an old and well-known device; but

I do claim as new and desire to secure by Letters Patent—

1. The construction of the drop-bar B with

a flattened portion, and a pin, *c*, upon its lower extremity, as herein shown and described, so that said pin *c* will pass through and lock the connecting-link, while the flattened portion will press upon, and by its weight maintain the link in a horizontal position, all as set forth.

2. The employment in each draw-head of

two separate springs, *G I*, of unequal tension, operating in the manner substantially as and for the purpose herein shown and described.

EDW. P. HOWLAND.
